ABSTRACT: A contact- and circuit-mounting board of unitary construction is contained within the housing of the switch unit. This board mounts fixed contacts which cooperate with other contacts carried by a reversing lever mounted adjacent the trigger. This board also mounts contact strips which are slidably engaged by contact fingers carried by the trigger thereby to define an on-off switch, a bypass switch and a variable resistor forming part of a speed control circuit. The elements of the circuit are contained on a printed circuit board, the latter being secured to the mounting board.

CONTACT- AND CIRCUIT-MOUNTING BOARD FOR TRIGGER-OPERATED SWITCH UNIT

OBJECTS OF THE INVENTION

A primary object of the present invention is the provision of a new and improved contact and circuit-mounting board for a trigger-operated speed control switch or the like.

Another object of the invention is the provision of a mounting board of the type described wherein such board supports first and second contact means cooperating respectively with third and fourth contact means, the latter being carried by a reversing lever and the trigger, respectively.

Still another object of the present invention is the provision of a mounting board of the type described, wherein such mounting board includes contact strips arranged to be slidably engaged by contact fingers carried by the trigger, one of such fingers and one of such strips defining a variable resistor forming part of a speed control circuit.

Another object of the present invention is the provision of a new and improved mounting board according to the foregoing object, wherein a printed circuit board is secured to such mounting board, the printed circuit board carrying the contact strip which defines the variable resistor as well as the various circuit elements defining the speed control circuit.

These and other objects and advantages of the invention will become apparent from the following specification disclosing a preferred embodiment shown in the accompanying drawings.

DESCRIPTION OF THE DRAWINGS

FIG. 1 is a side elevational view of a trigger-operated switch unit embodying the present invention, with an outer housing member being removed to expose one side of the unitary contact and circuit mounting board;

FIG. 2 is a side elevational view similar to FIG. 1 with the mounting board being removed to expose the contacts carried by the reversing lever and the trigger;

FIG. 3 is a section taken along the line 3-3 of FIG. 1;

FIG. 4 is a fragmentary section taken along the line 4-4 of FIG. 3;

FIG. 5 is an elevation of the side of the contact and circuit-mounting board opposite the side thereof shown in FIG. 1; and

FIG. 6 is an electrical schematic of the trigger-actuated switch unit connected with the motor of a portable electric tool or the like.

DESCRIPTION OF A PREFERRED EMBODIMENT

Referring particularly to FIG. 2, the trigger-operated switch unit of the present invention includes a housing member, generally designated 10, which has a sidewall 11, front and rear walls 12 and 14, respectively, and top and bottom walls 15 and 16, respectively. This housing member includes an elongated guideway 18 slidably receiving a reversing lever or bar 19 of the type disclosed and claimed in Frenzel U.S. Pat. No. 3,260,827; it will be understood the reversing lever is slidably mounted for reciprocal movement longitudinally thereof.

The reversing lever mounts a pair of contact balls 21, 22. As noted in FIG. 3, the contact ball 21 is engaged by a spring 23, the latter being received in a blind bore formed in one side of the reversing lever 19. This spring urges the ball 21 into engagement with fixed contacts as will be explained hereinbelow. It will be understood that the mounting for the contact ball 22 is identical to that just described for the contact 21.

The housing 10 includes a cavity 25, a portion of which defines a guideway 26 for slidably receiving the stem of a trigger 28. The trigger includes a blind bore 29 (FIG. 4) receiving a coil spring 30, one end of which spring receives a pin 31. This pin is secured to the rear wall 14 of the housing 10. The spring 30 acts to urge the trigger to its fully extended

position. Abutting engagement of trigger surface 32 with housing wall surface 32a serves as a stop to limit outward movement of the trigger.

The trigger may be provided with adjustable stop and lock means as disclosed and claimed in Frenzel U.S. Pat. No. 3,309,484. To this end, the trigger mounts an adjustment knob or button 33 which rotates a screw (not shown) in threading engagement with a lug 34 for moving the latter longitudinally of the trigger stem and relative thereto. This lug, which is arranged to abut stop means (not shown), acts as an adjustable stop to define the length of the trigger stroke. This lug also includes a latch surface 34a adapted to be engaged by the locking pin 35 (FIG. 4) so as to lock the trigger in any of its fully depressed positions. A locking button 36 is secured to the locking pin 35 and a coil spring 37 is provided for urging the locking button to its outermost position.

The trigger 28 carries a contact, generally designated 40, which contact includes three contact fingers 41, 42 and 43. As will be explained herein, these contact fingers engage fixed contacts supported by the mounting board which forms part of the present invention. As noted in FIG. 4, the contact 40 is received within a slot 44 formed in the trigger stem. The tension of the contact fingers is such that the latter, by reason of their engagement with the fixed contacts to be referred to hereinbelow, serve to retain the contact 40 in slot 44 without the aid of fastening means.

The unitary contact and circuit mounting board of the present invention is generally designated 45. As noted in FIG. 3, this board is secured to the housing member 10 and forms with the latter a closed housing space. Referring to FIG. 5, the mounting board 45 supports a horizontal row of equally spaced contacts 46-50. Different pairs of these contacts are engaged by the contact balls 21, 22 in response to movement of the reversing lever 19 as will be explained below.

The mounting board 45 further supports a first contact strip 52, another contact strip 53, and a contact button 54. It will be understood that the contact finger 41 is arranged for wiping engagement with the contact strip 52 and that the contact finger 42 is arranged for sliding or wiping engagement with the contact strip 53. When the trigger is fully depressed, the finger 42 separates from the strip 53 and comes into engagement with the contact button 54.

A printed circuit board, generally designated 57, is secured, as by means of an adhesive, to the mounting board 45. This circuit board is preferably of the type disclosed and claimed in the copending application of Conrad D. Robertson, Ser. No. 845,317, filed July 28, 1969, Case No. 690,503. To this end, the circuit board 57 supports a contact strip 58 formed of resistance material; this strip is engaged by the contact finger 43 and cooperates with the latter to define a variable resistor. The circuit board 57 also mounts (FIG. 6) a fixed resistor 59, an unencapsulated capacitor 60, a chip-type diode 61, a chip-type trigger device 62 and a chip-type semiconductor 63, such as a silicon controlled rectifier.

Reference should be had to the aforesaid Robertson application for a more detailed description of the electronic components on the circuit board 57 and the manner in which they are electrically connected. Preferably, the electronic elements on such board define a nonfeedback type of speed control system as disclosed and claimed in Gawron U.S. Pat. No. 3,209,228.

As shown in FIG. 6, the trigger-actuated switch is connected with a suitable motor of the reversible type having respective armature and field windings 65 and 66. The switch unit, when mounted in a tool and connected with the motor, may be energized from a suitable source of alternating current indicated by the lines 67, 68. The operation of the switch is as follows:

When the trigger is in its fully extended position, the contact finger 41 is separated from the strip 52, thereby breaking the circuit to the motor and defining an "off" position. After the trigger is depressed just a short distance, the finger 41 comes into sliding engagement with the contact strip 52, thereby completing a circuit to the motor through the speed control

system. As the trigger is continued to be depressed, the resistance is changed due to the sliding engagement of the contact finger 43 on the resistance strip 58, thereby increasing the speed of the tool motor as is more fully explained in the aforesaid Gawron patent. When the trigger reaches its fully depressed position, the contact finger 42 separates from the contact strip 53 and comes into engagement with the contact button 54 thereby bypassing the speed control system and energizing the motor directly from line current to operate the motor at maximum speed.

When the reversing lever 19 is in its forward position, the contact ball 21 engages contacts 46, 47 and the contact ball 22 engages contact buttons 48, 49. This will establish a current path through the field windings 66 in one direction which may be considered as the forward direction of rotation for the motor. When the reversing bar 19 is depressed, the contact ball 21 establishes a current path between contacts 47, 48 and the contact ball 22 establishes a current path between the contact buttons 49, 50. As is readily apparent from FIG. 6, this will establish a current flow through the field windings of the motor in the opposite direction thereby to rotate the latter in a reverse direction.

To prevent damage to the motor, it is desirable that the reversing lever be actuated only when the trigger is in its fully extended or "off" position to this end, the reversing lever 19 is provided with a pair of recesses 70, 71 in the underside thereof. A locking ball 73 is received in a cavity 74 in the trigger when the latter is in its fully extended position. The recess 74 in the trigger adjoins a camming surface 75. When the trigger is depressed, this camming surface 75 comes into engagement with the locking ball 73 and urges the latter upwardly into engagement with either the recess 70 or 71, depending on which recess is positioned over the ball 73. When the reversing lever bar 19 is in its innermost or reversed position, the recess 70 is disposed over the locking ball 73. When the reversing lever 29 is in its outermost or forward position, the recess 71 is disposed over the locking ball. The reversing lever is prevented from being moved when the locking ball 73 is received in either of the recesses 70, 71. It will be apparent that after the trigger 28 has been depressed just a short distance the locking ball 73 will be cammed into one of the other recesses 70, 71 to prevent movement to reversing bar 19. Reference should be had to the aforesaid Frenzel U.S. Pat. No. 3,260,827 for other forms of interlocking mechanism.

During the course of assembly, the locking ball 73 is dropped into the recess 74 through a pair of openings 76, 77. The opening 77 may be suitably plugged during final assembly of the trigger-actuated switch unit.

As noted in FIG. 1, the unitary mounting board 45 also supports a plurality of printed contact strips and formations including strips 81-83 to establish the appropriate current paths as indicated schematically in FIG. 6. The contact strips 81, 82 and 83 are each connected to a spring clip terminal; one of such terminals 85 is shown in FIG. 3 and will be seen to be disposed in an opening 86 which permits a lead wire (not shown) to be inserted for being gripped by the terminal 85.

The contact buttons 47, 48 and 49 are also engaged with spring clip terminals of the same structure. One of such terminals 87 is illustrated in FIG. 3 and is seen to be contained within an opening 88 for reception of a lead wire (not shown) to be engaged by the clip 87.

Preferably, the housing member 10 and mounting board 45, which are suitably secured together, are contained within an outer housing or casing (not shown). Any suitable construction well known to those skilled in the art may be provided for this purpose.

It will be seen that the present invention provides a unitary mounting board which supports the contacts to provide the necessary switching, both for "forward," "reverse," "on-off" and "bypass." Further, this board supports a circuit board which in turn mounts all of the electronic components to define a speed control system. Manifestly, the mounting board provides for easy and low-cost manufacture among other advantages.

We claim:

1. In a trigger-operated switch unit for installation in a portable electric tool or the like, the improvement comprising:
  - a. said unit including a housing;
  - b. a trigger movably mounted by said housing;
  - c. a reversing lever movably mounted by said housing;
  - d. first and second contact means in said housing and carried respectively by said trigger and said reversing lever for movement therewith;
  - e. means in said housing defining a unitary contact and circuit mounting board;
  - f. third and fourth contact means fixed to said mounting board and arranged for respective engagement by said first and second contact means;
  - g. first circuit elements on said board cooperating with said first and third contact means to define a circuit for energizing the associated tool motor upon actuation of said trigger; and
  - h. second circuit elements on said board cooperating with said second and fourth contact means to define a circuit for establishing the direction of rotation of the associated tool motor upon actuation of said reversing lever.

2. The improvement according to claim 1 further defined by:

- a. said second contact means being defined by a pair of contact elements carried by the reversing lever;
- b. said fourth contact means being defined by five contact members mounted on said board in spaced relation from each other; and
- c. said pair of contact elements establishing a current path through said said first and second contact members and another current path through said third and fourth contact members when said reversing lever is in one positions thereof, said pair of contact elements establishing a current path through said second and third contact members and another current path through said fourth and fifth contact members when said reversing lever is in the other of its two positions.

3. The improvement according to claim 1 further defined by:

- a. said first contact means including a plurality of contact fingers carried by said trigger for movement therewith; and
- b. said third contact means including a plurality of contact strips on said board arranged for being slidably engaged by respective contact fingers.

4. The improvement according to claim 3 wherein one of said fingers and one of said contact strips cooperate to define a variable resistor forming part of a variable speed control circuit constituting said first mentioned circuit.

5. The improvement according to claim 4 further defined by, a printed circuit board secured to said mounting board, said circuit board carrying said one contact strip.

6. The improvement according to claim 5 wherein said first circuit elements are mounted on said circuit board.

7. The improvement according to claim 1 further defined by:

- a. said second contact means being defined by a pair of contact elements carried by the reversing lever;
- b. said fourth contact means being defined by five contact members mounted on said board in spaced relation from each other;
- c. said pairs of contact elements establishing a current path through said first and second contact members and another current path through said third and fourth contact members when said reversing lever is in one of two positions thereof, said pair of contact elements establishing a current path through said second and third contact members and another current path through said fourth and fifth contact members when said reversing lever is in the other of its two positions;
- d. said first contact means including a plurality of contact fingers carried by said trigger for movement therewith; and

- e. said third contact means including a plurality of contact strips on said board arranged for being slidably engaged by respective contact fingers.
- 8. The improvement according to claim 7 wherein one of said contact fingers and one of said contact strips cooperate to define a variable resistor forming part of a variable speed control circuit constituting said first mentioned circuit.
- 9. The improvement according to claim 8 further defined by, a printed circuit board secured to said mounting board, said circuit board carrying said one contact strip.
- 10. The improvement according to claim 7 wherein said circuit board mounts said first circuit elements.
- 11. In a trigger-operated switch unit for installation in a portable electric tool or the like, the improvement comprising:
  - a. said unit including a housing;
  - b. a trigger movably mounted by said housing;
  - c. a reversing lever movably mounted by said housing;
  - d. first and second contact means in said housing which are moved in response to movements of said trigger and said

10

15

20

- reversing lever, respectively;
- e. said first contact means including a wiper finger;
- f. means in said housing defining a unitary contact and circuit mounting board;
- g. third and fourth contact means fixed to said mounting board and arranged for respective engagement by said first and second contact means;
- h. a printed circuit board secured by said mounting board with the former in coextensive physical contact with a portion of the latter, said printed circuit board carrying a plurality of elements defining a speed control circuit, one of such elements being a resistance strip slidably engaged by said wiper finger upon movement of said trigger; and
- i. other circuit elements on said board in direct physical contact therewith and cooperating with said second and fourth contact means to define a circuit for establishing the direction of rotation of the associated tool motor upon actuation of said reversing lever.
